CABINET

Robert J. Trotter, Pittsburgh, Pa.

Application August 22, 1932, Serial No. 629,788

4 Claims. (Cl. 312—141)

My invention relates to cabinets and particularly to a cabinet for bathroom cleaning brushes and cleaning powders.

In most bathrooms there is no cabinet space for the long-handled brush that is used for cleaning the closet bowl (commonly referred to as a commode brush), especially when the brush is wet. For this reason, the brush is commonly placed in an unsightly location. Besides this, there is generally the inconvenience that the brush must be dried out before it is put away. Another inconvenience found in most bathrooms is that the cleaning material and cleaning brushes are not kept in one place.

An object of my invention is to provide a cabinet of the above-mentioned type in which a commode brush or the like and cans of cleaning powder may be placed so that they may be kept in the bathroom but out of sight.

A further object of my invention is to provide a cabinet of the above-mentioned type in which a commode brush may be stored while wet and left there until it is to be used again.

A still further object of my invention is to provide a cabinet of the above-mentioned type which can be easily cleaned and which is economical to manufacture.

Other features of my invention will appear from the following description taken in connection with the accompanying drawing, in which

Figure 1 is a view in perspective of a cabinet constructed in accordance with my invention;

Fig. 2 is a view in perspective of a cabinet constructed in accordance with a modified form of my invention;

Fig. 3 is a view in perspective of the door of the cabinets shown in Figs. 1 and 2;

Fig. 4 is a view in perspective of the member that forms the main part of the cabinets shown in Figs. 1 and 2;

Fig. 5 is a view in perspective of the member that forms the top, the partition, and the bottom shelf of the cabinet shown in Fig. 2, and

Fig. 6 is a view showing an alternative construction for the guides for the sliding door.

Referring to Fig. 1, my invention comprises a cabinet which is tall compared with its width and depth and which is divided into two compartments 10 and 11, the left-hand compartment 10 being open at the top to permit the insertion of a long-handled brush and the right-hand compartment 11 being closed at the top.

The main part of the cabinet is formed from a single piece of sheet metal 12 bent to form the two sides 13 and 14 and the back 15 of the cabi-

net. This portion of the cabinet is shown in detail in Fig. 4. The front edges 16 and 17 of the sheet 12 are bent at right angles to the sides 13 and 14 to form the front guides of two grooves in which the cabinet door slides.

The back guides of the grooves are formed by strips 18 and 19 bent at right angles and welded to the sides 13 and 14. If desired, both front and back guides may be formed by bending the front edges of the sheet 12 as shown in Fig. 6.

The bottom of the cabinet is formed by a watertight pan 20 which is preferably drawn or pressed from a sheet of flat metal by means of suitable dies. The pan is spot-welded or otherwise fastened to the main portion of the cabinet.

The cabinet is divided into the open and closed compartments 10 and 11 by means of a single piece of sheet metal 21 which, in the design shown in Fig. 1, is bent at the ends to form a Z-shape member. The vertical portion of the member 21 has its edges 22 turned at right-angles thereto and these edges are welded to the sides 13 and 14 of the cabinet so that a partition extends from the top of the cabinet to within an inch or two from the bottom.

The upper part 23 of the Z-shape member forms the top of the closed compartment 11. The side edges 24 and the front edge are bent at right-angles to the top surface and the side edges are welded to the sides of the cabinet.

The lower part 25 of the Z-shape member extends into the brush compartment 10 to support the brush. It has slots 26 punched therein so that a wet brush may rest upon support 25 and the water drain into the pan 20 below.

Shelves 27 and 28 are provided in the closed compartment 11 for cans of cleaning powder, cleaning cloths, and the like. The shelves have their edges turned down at right-angles and the back edge and the side edges are welded to the partition 21 and to the sides 13 and 14, respectively.

The shelves and contents of the compartment 11 are concealed by a sliding panel or door 29. As shown in Fig. 3, the door comprises a single sheet of metal which has its edges turned over to stiffen it and to remove cutting edges. The top edge 30 of the door is bent at right-angles to the main part of the door to form a grip for raising and lowering the door.

The lower part of the cabinet is ventilated by means of holes 31 punched in the sides of the cabinet. Such ventilation causes the brush to dry more rapidly than it would otherwise.

A handle 32 is fastened to the top of the cabi-

net so that it may be carried easily. As the dimensions of the cabinet, in the preferred embodiment of the invention, are approximately 18 by 6 by 6 inches, it is light in weight. A hole 33 is provided in the back of the cabinet so that the cabinet may be hung on the wall if desired.

The cabinet shown in Fig. 2 is the same as that shown in Fig. 1 except that the Z-shape member is replaced by a U-shape member 34 which 10 is shown in detail in Fig. 5.

The upper part 35 of member 34 corresponds exactly to member 23 in Fig. 1.

The lower part 36 of member 34 is bent into the closed compartment 11 to form the bottom 15 shelf. The upper shelf is formed by a separate piece as shown in Fig. 1.

It will be noted that, in both cabinet designs, the back part of the cabinet bottom can be reached easily from the front of the cabinet for 20 cleaning.

In order to make a cabinet small enough to occupy but little space in the bathroom, the partition is set closer to the back of the cabinet than to the door so that just sufficient space is provided 25 between the partition and back to permit an average size commode brush to be inserted. In Figs. 1 and 2 the partition is about 2½ inches from the back 15. Because of this close fit, it was found that a clamp for catching the brush 30 handle could not be placed on the back of the cabinet below the hole 33, as it would not permit the insertion of the brush into the brush compartment 10. The difficulty was finally overcome by fastening a clamp 37 to the side 13 of the cabinet, 35 as shown in Fig. 2. Since the width of compartment 10 is considerably greater than the width of the brush, the brush will pass by the clamp 37 readily and, although the side of the brush will 40 swing against the side 13, the pressure will not be sufficient to flatten the wet brush. By thus suspending the wet brush from a clamp, the bottom of the brush is prevented from flattening out as it would if the brush were permitted to rest on the bottom of the cabinet.

45 It has been found that a cabinet height of approximately 18 inches is desirable to properly conceal the average commode brush and that a bottom approximately 6 inches square should be used to prevent the cabinet from upsetting easily. A cabinet having substantially greater width and 50 depth could not be as conveniently set out of the way in the bathroom. It will be noted that, by using a door which slides vertically, the danger of upsetting the cabinet when opening the door 55 is avoided.

Various modifications may be made in my invention without departing from the spirit and scope thereof, and I desire, therefore, that only such limitations shall be placed thereon as are 60 imposed by the prior art and are set forth in the appended claims.

I claim as my invention:

1. A cabinet having three sides formed from a single sheet, a substantially water-tight bottom therefor, a single sheet bent into a U-shape which forms a partition separating said cabinet into two compartments, one side of said U forming a closure at the top of one of said compartments, the other side of said U forming a shelf in said one compartment, and a door facing said shelf and forming one side of said cabinet. 10

2. A cabinet of the class described which is approximately square in the horizontal plane and which has a height at least twice a side of said square, said cabinet being divided into two compartments by means of a partition parallel to the back of the cabinet and spaced away from the bottom, said partition being closer to the back of the cabinet than to the front whereby the back compartment is the smaller of the two compartments, said smaller compartment being open at 20 the top, at least one shelf being in the larger of said compartments, and a door for enclosing said larger compartment, the bottom of said door being opposite the space between said partition and said bottom. 25

3. A commode brush holder comprising an integral member having a middle portion and two side portions at substantially right angles thereto to form the back and two sides of a receptacle, a bottom for said receptacle, a partition separating said receptacle into two compartments, said partition being in a vertical plane parallel to said back whereby one of said compartments is a back compartment and the other of said compartments is a front compartment, said partition being spaced away from said bottom, said back compartment being open at the top, said front compartment being closed at the top and having at least one shelf therein, and a door forming the front of said receptacle, the bottom of said door being opposite said space between the partition and the bottom of the receptacle whereby the back side of the bottom of the receptacle is readily accessible from the front thereof through the door. 40

4. A cabinet having a back and two sides formed from a single sheet, a substantially water-tight bottom therefor, a single sheet having a back portion, a top portion, and a bottom portion, said top and bottom portions being at an angle to said back portion, said back portion forming a partition spaced from said bottom and separating said cabinet into a back compartment and a front compartment, said top portion forming a closure at the top of said front compartment, said bottom portion being positioned underneath said top portion and forming a shelf in said front compartment, and a door forming the front of said cabinet. 50 55
